UNITED STATES PATENT OFFICE.

EMLYN MORRIS AND CLARENCE RINAMAN, OF PITTSBURG, PENNSYLVANIA.

WATER-INLET VALVE FOR FLUSH-TANKS.

No. 921,268.

Specification of Letters Patent.

Patented May 11, 1909.

Application filed March 10, 1908. Serial No. 420,171.

To all whom it may concern:

Be it known that we, EMLYN MORRIS and CLARENCE RINAMAN, citizens of the United States, both residing at Pittsburg, in the county of Allegheny and State of Pennsylvania, have invented certain new and useful Improvements in Water - Inlet Valves for Flush-Tanks; and we do declare the following to be a full, clear, and exact description 10 of the invention, such as will enable others skilled in the art to which it appertains to make and use the same, reference being had to the accompanying drawings, and to the figures of reference marked thereon, which 15 form a part of this specification.

This invention relates to an improved inlet-valve for flush-tanks; and it consists in the certain details of construction; and combination of parts, as will be fully described 20 hereinafter.

In the accompanying drawings:—Figure 1 is a central side sectional elevation of our improved inlet-valve for flush-tanks, the same being constructed and arranged in accordance 25 with our invention. Fig. 2 is an end elevation of the same, a portion of the top being broken away. Fig. 3 is a detailed side elevation of the movable centrally-arranged tube and top extension of the same.

To put our invention into practice, and thereby provide a valve for regulating and controlling the flow of water into flush-tanks for water-closet purposes, we provide a cylindrical shell in two parts, an upper and lower, the one joined to the other. The lower section 2, of this shell comprises a downwardly-extending threaded member 4, having a central bore 6, a flange 3 and upwardly-extending externally threaded boss 40 by which means it is attached to the upper section 2' of the shell. The lower section 2 of the shell is attached to the tank 1, by means of a large nut 5, in the usual manner. The upper section of the shell comprises a body-portion 2', cylindrical in form, the lower end of which is formed with an internal thread to engage with that of the lower section 2 and bring the two parts in perfect axial alinement. This upper section 2' is 45 also formed with an enlarged portion 13, with openings 15 at either side, and also with oppositely-arranged slots 8' near the upper end, through which an operating bar 25 passes. Arranged within the bore of the upper section 2' is a stuffing-box 17, having a

serrated flange 16, and threaded to engage a portion of the interior thread of said section, by means of which packing 18 may be confined about a centrally located tube 9. This tube 9 is formed with an enlarged upwardly-extending portion 7, an intermediate circumferential groove 11, a recess 8 near the top and several small perforations 10, said perforations being located near the top of the reduced part of said tube. The circumferential groove 11 is for the purpose of holding a washer 12, which operates within a cylindrical bore of the gland 17 of the stuffing-box. 60

Attached to or formed integral with the upper section 2' of the shell are oppositely-arranged brackets 14 and 15, the one bracket 14 supporting a bell-crank and the other 15, the one end of a pivoted bar 25. This bar 25 is pivoted at one end by means of a bolt 27, to the bracket 15, and is formed with upper 70 and lower enlarged portions 26, which portions are located within the recess 8 of the plug 7, and the other end of said bar is pivoted by a bolt 24 to a short coupling link 22, which in its turn is connected by a bolt 23 75 to one end of a bell-crank. This bell-crank consists of a horizontal part 21 and a vertically-arranged arm 20, the upper extremity of which is formed with a threaded boss to support the rod 28, of an ordinary float 29. 80

In operation the water-supply pipe is connected to the threaded portion 4 at the base of the shell by the use of ordinary fittings. The water being in the tank 1 the float 29, and the parts of the valve will be in the position shown at Fig. 1 of the drawings. When the tank is flushed the float descends thereby elevating the horizontal part 21 of the bell-crank, which movement is transmitted to bar 25, giving its free end an upward movement, thereby elevating the tube 9, to bring the perforations 10 of the same above the level of the gland and permit the water to flow to refill the tank, and when the water has reached its normal level the perforations 100 10, will have moved to a position to shut-off the flow of water. 95

Various slight modifications and changes may be made in the details of construction without departing from the spirit of the invention. Therefore we do not wish to confine ourselves to the exact construction, shown and described, but wish to claim all such as would come properly within the general scope of the invention. 105

Having thus described our invention, what we claim, and desire to secure by Letters Patent, is:

An automatic inlet-valve for flush tanks, comprising a shell formed in two sections, the one joined to the other in a vertical line and having a longitudinal bore reduced to form a seat for suitable packing, a centrally located vertically-moving perforated tube having an enlarged upper portion and an intermediate groove, a gland arranged to compress said packing about said tube, a second packing attached to said tube and adapted to fit within said gland, openings in the upper section of the shell to permit

the escape of the water, a recess formed in the upper portion of said tube, a bar operating in said recess means for pivoting one end of said bar enlargements formed on the bar to fill the recess, a bell-crank connected to said bar, means for pivoting said bell-crank and means for attaching a float to the upper end thereof, as described. 20

In testimony whereof, we affix our signatures, in presence of two witnesses.

EMLYN MORRIS.

CLARENCE RINAMAN.

Witnesses:

Wm. G. WALTER,

Wm. T. MAXWELL.
